THREAD STORE DEVICE

Walter F. Knebusch, Rocky River, Ohio, assignor
to Industrial Rayon Corporation, Cleveland,
Ohio, a corporation of Delaware

Application February 18, 1935, Serial No. 7,116
Renewed February 25, 1938

18 Claims. (CL 242—53)

This invention relates to means for adjusting thread store devices of a type adapted, during operation thereof, to wind thread or other material on the device in a plurality of successive generally helical turns which turns are bodily advanced lengthwise of the device by the action of the elements thereof. The invention has application, at least in certain of its aspects, to thread store devices generally. It has particular application to thread store devices taking the form of reels made up of a plurality of rigid, generally cylindrical reel members each of which has a periphery comprised of a plurality of longitudinally extending bar members in which the bar members of the respective reel members are alternately disposed and in which the axes of the reel members are spaced from and inclined to each other.

Specifically, the invention relates to means for adjusting the pitch of the generally helical turns of thread or other material advanced by the thread store device during operation thereof. Among other things, it is an object of the invention to provide means for adjusting the pitch of the generally helical turns of thread or other material by adjustment of the degree of inclination of the axes of the members going to make up the device. Other objects of the invention will be in part pointed out hereinafter and will be in part apparent from the following illustrative description of the preferred embodiment of the invention, which comprises a reel of the type above mentioned adapted to advance thread or the like in generally helical form.

In the drawing, Fig. 1 is a longitudinal sectional elevation, on line 1—1, Fig. 2, through one form of reel embodying the invention. Fig. 2 is a plan corresponding to Fig. 1. Fig. 3 is a detail sectional elevation on a larger scale on line 3—3, Fig. 2. Fig. 4 is a detail sectional elevation on line 4—4, Fig. 3. Fig. 5 is an end view of the reel from the left in Fig. 1. Fig. 6 is a detail sectional elevation on line 6—6, Fig. 1. Like reference characters serve to identify like parts in all figures of the drawing.

While reels embodying the invention may be employed in the handling of various kinds of materials, they may be used to particular advantage in the handling of thread or the like which is subjected to a liquid processing treatment while stored on the reel. Thus the reel described hereinafter as embodying the invention is shown as designed for employment in an apparatus for the continuous processing of artificial silk thread. However, inasmuch as the invention relates particularly to the means for varying the lead of the

helical turns of thread which are produced by and which travel along the reel, description of that portion of the mechanism will be sufficient for the purposes of this application.

In the drawing, the reference character 1 designates a suitable gear casing of hollow box form designed to enclose the gears for driving a plurality, say five, of the reels. In said casing is journaled a driving shaft 2 which at intervals along its length is provided with spiral gears 3, one for each reel to be driven. Each of said spiral gears meshes with a spiral gear 4 rotatable loosely upon a shaft 5 but capable of driving connection with said shaft by operation of a clutch indicated generally at 6, the movable clutch member being operated in any suitable manner, as by a lever 7. Shaft 5 is journaled in opposite walls of the gear casing, projecting from one side thereof where its projecting portion both supports and drives the reel now to be described.

The reel shown comprises two rigid cage members, one of which is a concentric reel member 8. The latter, shown as of generally cylindrical form, embodies a hollow cylindrical body 9 provided with a hub 10 within which is rigidly fastened a sleeve 11 keyed to or otherwise secured to rotate with the shaft 5. Said hub is fastened to the shaft in any suitable manner, as by a nut 12 threaded upon its end. The outer cylindrical body portion 9 is provided with a series of longitudinally extending recesses 13 formed between radially extending longitudinal bars 17. This reel member 8 is called the concentric member because all of its parts are symmetrically disposed about the axis of shaft 5, so that when the shaft 5 is rotated, the reel member rotates concentrically about the shaft axis. It is rigid in the sense that all of its parts are relatively immovable with respect to each other and with respect to shaft 5.

In the recesses 13 of the concentric reel member lie the bars 18 of the second rigid reel member; i. e., the eccentric reel member, said member comprising inner and outer ring-like members 19, 20. Such eccentric reel member, like the concentric reel member, is rigid in the sense that all of its parts are immovable with respect to each other. The ring-like members 19, 20 comprising it are respectively externally and internally tapered, being secured together by screws 21 which, when screwed up to the home position, securely clamp the bars 18 in place between the inner and outer ring-like members. Inner ring-like member 19 is provided with a central sleeve 22 journaled upon a tubular member 23 suitably attached, as by the

set screw 24, to a supporting member 25 adjustably mounted upon the front wall of the gear casing 1. The eccentric reel member is so called because, while it is of generally cylindrical form, the axis thereof is concentric with the axis of member 23, which is so mounted that its axis is both slightly offset from and inclined with relation to the axis of shaft 5.

In the illustrated reel, the axis of the eccentric reel member lies in a plane parallel to the axis of the concentric reel member; so that the inclination thereof is with respect to a line in such plane parallel to the axis of the concentric reel member. In the operation of the reel shown rotation of the shaft 5 by the gearing and through the clutch above described drives the concentric reel member, which, through bars 17, 18, drives the eccentric reel member. In operation, the offset and inclined relation of the axes of the two reel members causes the thread led to the reel to be wound upon it as a series of spaced helical turns which progress bodily along the reel to its discharge end.

The reel as a whole is of cantilever form in the sense that it is both supported and driven from one end only; to-wit, from the end from which shaft 5 is driven.

In the embodiment shown, the supporting member 25 is provided with a channel 26 communicating with a passage 27 in member 23 leading to the bearing surfaces between member 23 and the sleeve 22, channel 26 being provided at its outer end with a grease gun receiving nipple device 28 for supplying lubricating grease or other material. Member 25 is provided with oppositely disposed arms 29, each of which near its outer end has a curved slot 30 to receive a cap screw 31 threaded through said slot into an opening in a block 32 integral with and forming a part of the front wall of the gear casing 1. Each block 32 is wide enough to receive the ends of the arms 29 of two adjacent reel supports. Further, each block has its front face; i. e., the face which is presented to an operator standing at the front of the machine, inclined from the vertical. In the illustrated embodiment, when viewed from the front of the machine or from the left in Fig. 1, the front surface of the block is inclined downward away from the observer. The rear faces of the end portions of arms 29 which are in contact with the blocks are correspondingly inclined.

The parts above described are so formed that when the member 23 is secured in its support 25 and said support is clamped to the gear casing 1 with its arms 29 extending horizontally, the axis of the member 23, and consequently the axis of the eccentric reel member, extends horizontally in a plane parallel to the horizontal plane passing through the axis of shaft 5. The axis of the member 23, and therefore the axis of the eccentric reel member, is, however, slightly inclined with relation to the axis of the shaft 5. The amount of the inclination determines the pitch of the turns of thread wound in helical form upon the reel and progressively advanced along it. A very slight variation in the degree of inclination produces material variation in the spaces between turns of thread.

With the arrangement described, by loosening the cap screws 31 in the opposite arms of supporting member 25 and turning said arms substantially about the axis of shaft 5, thus raising one of its arms and lowering the other, the degree of inclination of the reel member carried by said supporting member 25 may be increased or

diminished so as to adjust it to any desired value within reasonable limits. Specifically, in the case of an operator facing the reel from the left in Fig. 1, if member 25 is adjusted so as to drop its right hand arm and raise its left hand arm, the effect will be to swing the member 25 laterally toward the lower part of Fig. 2. The inclined surfaces of the blocks 32 are in effect cam faces, while member 25, which has corresponding cam faces at the ends of its arms 29, constitutes a follower.

In the arrangement described, the two rigid reel members are both of generally cylindrical form with their respective sets of bars in alternating relation. Each of the rigid reel members rotates about a definite axis, the concentric reel member rotating about the axis of shaft 5 and the eccentric reel member about the axis of member 23. The adjustment described provides simple means for varying the inclined relation between the axes. All parts are readily accessible and the adjustment is convenient to the operator, but the reels are nevertheless held firmly in the desired position.

Further advantages of the invention will be apparent to those skilled in the art.

It will be understood that the thread store device herein shown and described is illustrative only and is not intended to limit the scope of the invention. It is apparent that numerous modifications may be made in the embodiment illustrated and that various other embodiments of the invention may readily be devised. Obviously, thread store devices of the kind contemplated by the invention may be applied to various other uses than those above indicated. Other changes also may be made without in any way departing from the spirit of the invention, the scope of which is intended to be indicated in and by the accompanying claims.

It is intended that the patent shall cover, by suitable expression in the appended claims, whatever features of patentable novelty reside in the invention.

What I claim is:

1. A reel comprising two sets of interdigitating bar members each of which sets is substantially circular in cross section; a frame in which one set of bar members is journaled; a support on which the other set of bar members is journaled; and means for varying the relation of said sets of bar members comprising arms on said support adjustably connected to said frame.

2. A reel comprising two sets of interdigitating bar members each of which sets is substantially circular in cross section; a frame in which one set of bar members is journaled; a support in which the other set of bar members is journaled; and means for varying the relation of said sets of bar members comprising arms on said support connected to said frame.

3. A reel comprising two reel members; a frame in which one of said members is journaled; a support on which the other member is journaled; and means for varying the relation of the second member to the first member comprising arms on said support adjustably connected to the frame having inclined faces held against cooperating faces on the frame.

4. A reel comprising two reel members; a frame in which one of said members is journaled; a support on which the other member is journaled; and means for varying the relation of the second member to the first member comprising arms on said support adjustably connected to the frame

having inclined faces held against corresponding-
ly inclined faces on the frame.

5. A reel comprising two reel members; a frame
in which one of said members is journalled; a
support on which the other member is jour-
nalled; and means for varying the relation of the
second member to the first member support
comprising arms on said supporting means ad-
justably connected to the frame having faces
10 held against inclined cooperating faces on the
frame.

6. A thread store device comprising two thread-
advancing elements normally inclined with re-
spect to each other; a frame supporting one of
15 said thread-advancing elements; and, adjustably
associated with said frame, means supporting the
other of said thread-advancing elements, said
supporting means embodying an inclined surface
held against a cooperating surface on said frame.

20 7. A thread store device comprising two thread-
advancing elements normally inclined from par-
allelism with each other; a frame supporting one
of said thread-advancing elements; and, adjust-
ably associated with said frame, means support-
25 ing the other of said thread-advancing elements,
said supporting means embodying an inclined
surface held against a correspondingly inclined
surface on said frame.

8. A thread store device comprising two thread-
advancing elements normally inclined from par-
allelism with each other; a frame supporting one
of said thread-advancing elements; and, adjust-
ably associated with said frame, means support-
35 ing the other of said thread-advancing elements,
said frame embodying an inclined surface against
which is held a cooperating surface on said sup-
porting means.

9. A reel comprising two sets of interdigitating
40 bar members each of which sets is substantially
circular in cross section; a frame in which one
set of bar members is journalled; a support in
which the other set of bar members is journalled;
and means for varying the relation of said sets
45 of bar members comprising arms on said support
connected to said frame in a manner permitting
selective movement of said support while in con-
tact with said frame.

10. A thread store device comprising two
thread-advancing elements normally inclined
50 from parallelism with each other; a frame sup-
porting one of said thread-advancing elements;
and, adjustably associated to said frame, means
supporting the other of said thread-advancing
elements, said supporting means including a cam
55 face and a follower held against said cam face.

11. A thread store device comprising two
thread-advancing members each of which is sub-
stantially circular in cross section; a frame sup-
60 porting one of said thread-advancing members;
and, adjustably associated with said frame,
means supporting the other of said thread-ad-
vancing members, said supporting means in-
cluding a cam face and a follower held against
65 said cam face.

12. A winding reel comprising a frame mem-
ber; a first set of bar members which set is sub-
stantially circular in cross section rotatably sup-
ported from said frame member; a second set of
70 bar members alternating with those of said first
set, said second set of bar members being sub-
stantially circular in cross section; a supporting
member on which said second set of bar members
is journalled for rotation, the axis of rotation of
75 said second set of bar members being at all times
coincident with the axis of said supporting mem-

ber; and means adjustably connecting said sup-
porting member and said frame member whereby
said supporting member may be moved to a
variety of positions in which the axis of rota-
tion of said second set of bar members is in in-
clined relation to the axis of rotation of said first
set of bar members.

13. A winding reel comprising a frame mem-
ber; a shaft rotatably journalled in said frame
member; a first set of bar members mounted con-
centrically of said shaft, said set of bar members
being substantially circular in cross section; a
second set of bar members alternating with those
of said first set, said second set of bar members
being substantially circular in cross section; a
supporting member having a surface of revolu-
tion on which said second set of bar members is
journalled for rotation, the axis of rotation of
said second set of bar members being at all times
coincident with the axis of said surface of revolu-
tion; and means adjustably connecting said sup-
porting member and said frame member whereby
said supporting member may be moved to a va-
riety of positions in which the axis of said surface
of revolution is in inclined relation to said shaft.

14. A winding reel comprising a frame mem-
ber; a shaft rotatably journalled in said frame
member; a first set of bar members mounted
concentrically of said shaft, said set of bar members
being substantially circular in cross section; a
second set of bar members alternating with
those of said first set, said second set of bar mem-
bers being substantially circular in cross section;
a supporting member surrounding said shaft
having a surface of revolution on which said sec-
ond set of bar members is journalled for rotation,
the axis of rotation of said second set of bar
members being at all times coincident with the
axis of said surface of revolution; and means
adjustably connecting said supporting member
and said frame member whereby said supporting
member may be moved to a variety of positions
in which the axis of said surface of revolution is
in inclined relation to the axis of rotation of said
shaft.

15. A winding reel comprising a frame mem-
ber; a first set of bar members rotatably sup-
ported from said frame member, said set of bar
members being substantially circular in cross sec-
tion; a second set of bar members alternating
with those of said first set, said second set of bar
members being substantially circular in cross sec-
tion; a supporting member on which said second
set of bar members is journalled for rotation, the
axis of rotation of said second set of bar members
being at all times coincident with the axis of said
supporting member; and means providing an ad-
justable connection between said supporting
member and said frame member comprising co-
operating cam surfaces at the juncture of the
supporting member and said frame member,
whereby said supporting member may be moved
to a variety of positions in which the axis of ro-
tation of said second set of bar members is in in-
clined relation to the axis of rotation of said first
set of bar members.

16. A winding reel comprising a frame mem-
ber; a first set of bar members rotatably sup-
ported from said frame member, said set of bar
members being substantially circular in cross 70
section; a second set of bar members alternating
with those of said first set, said second set of bar
members being substantially circular in cross sec-
tion; a supporting member on which said second
set of bar members is journalled for rotation;

and means providing an adjustable connection between said supporting member and said frame member comprising at least one cam surface on said supporting member extending transversely of the axis of rotation of said second set of bar members and at least one cooperating cam surface on said frame member, whereby said supporting member may be moved to a variety of positions in which the axis of rotation of said second set of bar members is in inclined relation to the axis of rotation of said first set of bar members.

17. A winding reel comprising a frame member; a first supporting member carried by said frame member; a first set of bar members mounted on said first supporting member, said set of bar members being substantially circular in cross section; a second set of bar members alternating with and in inclined relation to those of said first set, said second set of bar members being substantially circular in cross section; and a sec-

ond supporting member surrounding said first supporting member on which is rotatably mounted said second set of bar members, said second supporting member having therein an opening through which said first supporting member passes which opening is substantially greater than the periphery of said first supporting member.

18. A winding reel comprising a frame member; a shaft rotatably journaled in said frame member; a first set of bar members mounted concentrically of said shaft, said set of bar members being substantially circular in cross section; a second set of bar members alternating with and in inclined relation to those of said first set; and a supporting member surrounding said shaft on which supporting member said second set of bar members is rotatably mounted, said supporting member comprising a concentric hollow cylinder.

CERTIFICATE OF CORRECTION.

Patent No. 2,188,359.

January 30, 1940.

WALTER F. KNEBUSCH.

It is hereby certified that error appears in the printed specification of the above numbered patent requiring correction as follows: Page 2, second column, line 61, claim 2, after "frame" and before the period, insert in a manner permitting movement of said support to a variety of positions in which said sets of bar members are in inclined relation to each other; page 3, first column, line 7, claim 5, strike out the word "support"; line 8, same claim, for "supporting means" read support; line 13-14, claim 6, for "with respect to" read from parallelism with; line 52, claim 10, for "to" read with; and that the said Letters Patent should be read with this correction therein that the same may conform to the record of the case in the Patent Office.

Signed and sealed this 19th day of March, A. D. 1940.

(Seal)

Henry Van Arsdale,
Acting Commissioner of Patents.
